UNITED STATES PATENT OFFICE.

GEORGE L. TULLY AND PITT H. HERBERT, OF SOUTHBRIDGE, MASSACHUSETTS,
ASSIGNORS TO AMERICAN OPTICAL COMPANY, OF SOUTHBRIDGE, MASSACHUSETTS, A VOLUNTARY ASSOCIATION OF MASSACHUSETTS.

GOGGLES.

1,269,981.

Specification of Letters Patent. Patented June 18, 1918.

Application filed June 3, 1914. Serial No. 842,559.

To all whom it may concern:

Be it known that we, GEORGE L. TULLY and PITT H. HERBERT, citizens of the United States residing at Southbridge, in the county of Worcester and State of Massachusetts, have invented certain new and useful Improvements in Goggles, of which the following is a specification.

Our invention relates to improvements in goggles and has particular reference to an improved form of goggle which may be readily adapted to the facial requirements of different wearers.

The leading object of our invention is the provision of an improved goggle which may be readily and easily adjusted without the necessity of the employment of tools and which may be correctly and satisfactorily fitted to varying sizes and shapes of faces.

A further object of our invention is the provision of a goggle which shall be simple and inexpensive of construction, shall permit of great adjustability and which shall be neat and attractive in appearance.

Another object of our invention is the provision of a simple one piece construction of combined bridge, frame and bearing member for a goggle.

Other objects and advantages of our improvement should be readily apparent by reference to the following description taken in connection with the accompanying drawings, and it will be understood that we may make any modifications in the specific details of construction shown and described within the scope of the appended claims without departing from or exceeding the spirit of our invention.

Figure I represents a front elevation of one embodiment of our invention.

Fig. II represents a top plan view thereof.

Fig. III represents a sectional view on the line III—III of Fig. I.

Fig. IV represents a front view of a slightly modified construction.

Fig. V represents a sectional view on the line V—V of Fig. IV.

Fig. VI represents a fragmentary plan view of the blank for forming our combined one piece construction.

Fig. VII represents a sectional view illustrating the blank illustrated in Fig. VI in use.

Fig. VIII represents a view of a slightly different bridge.

In the drawings, in which similar characters of reference are employed to denote corresponding parts throughout the several views, the numeral 1 designates the lenses which are inclosed within the rims or frame pieces 2. These frame pieces 2 may have either integral therewith or separate therefrom the eye cup portions 3 if desired, although it will be understood that our invention may be employed simply with the temples or other retaining members 4 for securing the device in position and the eye cups 3 may be dispensed with should this structure prove preferable.

Connecting the said lens engaging frames 2 is our improved bridge member comprising the central bar portion 5 bent at its end and extending reversely in the portion 6 and having a second bend formed therein to provide the outwardly extending arm 7 which is attached to the frame 2.

This construction will probably be best understood by reference to Figs. II and VII and it will be seen that our bridge, therefore, comprises a central cross piece having a doubly folded member therebehind. Consequently the goggle or mounting may be readily adapted to faces having different widths of noses, it being merely necessary to draw outwardly on the frame 2, thus to a greater or less degree opening up the loops at the rear of the bar 5 and increasing the pupillary distance of the mounting as desired; on the other hand tightening up of these loops will serve to decrease the pupillary distance.

A further great advantage of our improved construction is the possibility, however, of increasing the distance between the lenses without the necessity for disturbing these loops. This adjustment is attained by rotation or shifting of the lenses as indicated by the dotted lines in Fig. I. We believe the term rotation can best be employed to describe this adjusting movement, since the rims are grasped and simply given a twisting or rolling movement away from each other, which serves to move the same outward without substantially disturbing the horizontal alinement thereof, and consequently is a particularly desirable adjust-

ment, this movement causing some slight moving of the arms 6 and 7, but a relatively small amount of bending at these arms attaining the desired adjustment without disturbing the symmetrical appearance of the mounting.

It is to be noted in the form illustrated in Figs. I to III inclusive, we have shown the frames 2 and eye cups 3 as integral with each other, and further as having stamped therefrom the guard member 8, the whole thus being formed in a unitary structure, although it will be understood that we may dispense with the guard 8 or may form the same separate from and secured into the eye cups or the frames proper, or even to the bridge, as may prove most desirable.

In Figs. IV and V, we have illustrated a further improvement of our invention in which we cover the cross piece 5 with a chenille or other suitable covering 9, thus rendering the appearance of the same extremely attractive and desirable, and imparting a rich and dressy look to the goggle.

In Figs. VI and VII, we have illustrated a unitary one piece construction comprising the cross piece 5 of sufficient length to permit of looping thereof into the portions 6 and 7, the eye wire 2 being integral with the member 5 and having projecting preferably from the opposite side thereof from that on which the member 5 is located, a second arm 10 carrying the guard 8. The use of this form of our invention will probably be best understood by reference to Fig. VII, from which it will be seen that the eye wire is shaped to fit within the cup 3, although if preferred it may be constructed to embrace the cup 3 and retain the cup and lens in position in correct relation to each other, while the arm 10 is preferably rearwardly looped around the cup to bring the guard into correct position to permit of adjustment of the guard while the bridge is looped or folded in the portions 6 and 7 forwardly of the eye wire or frame 2 and has the cross extending portion 5 serving to connect the opposite eye wire or frame members 2, as will be readily understood by those conversant with the art.

From the foregoing description taken in connection with the accompanying drawings, the construction and advantages of our improved goggle should be readily apparent, and it will be seen that we have provided a neat, simple and attractive goggle which may be readily constructed, which

will have a bridge permitting of maximum adjustment of the lenses in any desired direction either by rolling movement, as illustrated in Fig. I or by opening of the bends as may prove most desirable to secure the exact fit, one which on account of the covering of the bridge, as shown in Figs. IV and V, and the provision of the guard 8, will be extremely comfortable under all service conditions and one which may if desired be constructed from a single piece of material thus lessening the labor cost of manufacture and making a more firm and stable mounting less liable to come apart than could otherwise be provided.

We claim:

1. In a device of the character described, the combination with a pair of lens-receiving frames, of a connecting member for said frames disposed a distance above the centers thereof and comprising a horizontal cross-piece terminating at each end into oppositely extended parallel arranged loops located in the rear of and concealed by the front cross-piece, said loops being disposed in substantially parallel alinement with the axis of the lenses and secured directly to the lens frames at a point above the center thereof and in substantially horizontal alinement with the center crosspiece, whereby the loops afford satisfactory in and out and twisting adjustment of the lens frames relative to each other while substantially concealed by the frontal crosspiece.

2. In a device of the character described, the combination with a lens rim member adapted to be curved to receive the edge of a lens, of an arm extending to one side of said rim member and terminating in a guard or bearing member, and a second arm extending from the opposite side of the rim member at a point above the point of extension of the guard member and adapted to be formed into oppositely extended parallel arranged loops disposed in substantially parallel alinement with the axis of the lenses, and a straight crosspiece connecting certain of said loops to provide a bridging member substantially as and for the purpose described.

In testimony whereof we affix our signatures in presence of two witnesses.

GEORGE L. TULLY.
PITT H. HERBERT.
